US00D980435S

(12) **United States Design Patent** (10) **Patent No.:** **US D980,435 S**
Conner (45) **Date of Patent:** **** Mar. 7, 2023**

(54) **EARLOBE SUPPORT**

(71) Applicant: **Monica Conner**, Denver, CO (US)

(72) Inventor: **Monica Conner**, Denver, CO (US)

(**) Term: **15 Years**

(21) Appl. No.: **29/836,763**

(22) Filed: **Apr. 28, 2022**

Related U.S. Application Data

(63) Continuation of application No. 17/169,284, filed on Feb. 5, 2021, now abandoned.

(51) **LOC (14) Cl.** **24-02**

(52) **U.S. Cl.**

Paul N. Dunlap, Esq.

(57) **CLAIM**

The ornamental design for an earlobe support, as shown and described.

DESCRIPTION

FIG. 1 is a front perspective view.

FIG. 2 is a front elevation view.

FIG. 3 is a right side elevation view.

FIG. 4 is a top plan view.

FIG. 5 is a bottom plan view.

FIG. 6 is a left side elevation view; and,

FIG. 7 is a rear elevation view.

Dashed lines show an optional hole that is not a part of the claim. The mirror image is also claimed.

1 Claim, 2 Drawing Sheets

US D980,435 S
